ADULT URINE SPECIMEN COLLECTOR

Edward J. Hill, Bloomfield Hills, Mich., assignor of one-half to E. Doris Ansteth, Birmingham, Mich.

Filed May 11, 1962, Ser. No. 70,095

Term of patent 14 years

(Cl. D83—1)

FIG. 1 is a top plan view of an adult urine specimen collector embodying my new design; and

FIG. 2 is a side elevational view; and

FIG. 3 is a bottom view; and

FIG. 4 is a front elevational view; and

FIG. 5 is a rear elevational view.

I claim:

The ornamental design for an adult urine specimen collector, substantially as shown.
